(57) **CLAIM**

The ornamental design for a reflective bar for an interactive whiteboard, as shown and described.

DESCRIPTION

FIG. 1 is a back elevational view of a reflective bar for an interactive whiteboard showing the design;

FIG. 2 is a top view thereof;

FIG. 3 is a left side elevational view thereof;

FIG. 4 is a front elevational view thereof;

FIG. 5 is a right side elevational view thereof;

FIG. 6 is a bottom view thereof;

FIG. 7 is a back view of the reflective bar in an extended position;

FIG. 8 is a top view of the reflective bar of FIG. 7;

FIG. 9 is a left side elevational view of the reflective bar of FIG. 7;

FIG. 10 is a front elevational view of the reflective bar of FIG. 7;

FIG. 11 is a right side elevational view of the reflective bar of FIG. 7;

FIG. 12 is a bottom view of the reflective bar of FIG. 7;

FIG. 13 is a front elevational view of a plurality of the extended reflective bars in use on an interactive whiteboard with a digitizer;

FIG. 14 is a perspective view of the reflective bar of FIG. 2; and,

FIG. 15 is a perspective view of the extended reflective bar of FIG. 8.

The broken lines are included for purposes of illustration and form no part of the claimed design.
